UNITED STATES PATENT OFFICE.

WILHELM BACHNER, OF STUTTGART, GERMANY.

APPARATUS FOR COOLING BEER OR OTHER LIQUIDS.

SPECIFICATION forming part of Letters Patent No. 634,792, dated October 10, 1899.

Application filed October 1, 1898. Serial No. 692,425. (No model.)

To all whom it may concern:

Be it known that I, WILHELM BACHNER, a citizen of the German Empire, residing at Stuttgart, in the Kingdom of Würtemberg, 5 Germany, have invented certain new and useful Improvements in Apparatus for Cooling Beer or other Liquids; and I do hereby declare the following to be a full, clear, and exact description of the invention, such as will 10 enable others skilled in the art to which it appertains to make and use the same.

This invention relates to apparatus for cooling and dispensing beer and other liquids; and it consists, substantially, in such features 15 of improvement as will hereinafter be more particularly described.

As is well known, a large number of different ice-chests already exist with discharging devices for effervescent drinks, more particularly beer and the like, in which the beer contained in a cask or in a separate container in the ice-chest is discharged by air or gas pressure, and more particularly by means of carbonic acid. The majority of consumers, however, desire that no carbonic acid be used on the beer when drawing off the same, and the present invention is designed to meet their wishes in providing an apparatus in which the beer is discharged without carbonic-acid 25 pressure.

A further object of the invention is to provide means for discharging the beer through the direct pressure of a movable ice chest or receptacle, the effective action of said receptacle being controlled by the weight of the ice contained therein.

Other objects of the invention will more fully appear hereinafter.

The apparatus embodying the present improvements is shown in the accompanying drawings, Figures 1, 2, and 3 being three vertical sections, and Fig. 4 a horizontal section.

The beer or other liquid is pumped from the cask by air-pressure into a cylinder or receptacle therefor B, vertically mounted on feet b' in an air-tight refrigerator A, said cylinder or receptacle being kept tightly closed by means of a vertically-adjustable hollow piston C with washer-rings c'. The hollow piston is provided with a grate c² and is utilized as an ice container or chest.

In order that the cylinder B may not be

damaged when filling ice into the apparatus, the movable ice-chest or piston C is provided at its upper part with an annular protective 55 casing C' of U-shaped longitudinal section, between the two walls of which the upper part of the beer-cylinder B is received and cannot be damaged by pieces of ice thrown into the apparatus.

The beer pumped into the cylinder stands in the same under direct pressure owing to the weight of the movable ice-chest or piston C, together with its protective casing C' and also the ice or melted ice contained therein, 65 which weight may be increased by a weight-box U, mounted above in the casing C' and more or less counterbalanced, if desired, by means of adjustable counterweights f', supported on cords or chains F, traveling over 70 pulleys f, supported at the upper part of the refrigerator-chest A. The cylinder B is placed in the highest part of the refrigerator-chest, which part is provided with a cover a, the said refrigerator-chest having in front a lower side-board-like projecting part A', which is provided at the top with a removable cover A².

The beer in the cylinder B, which surrounds the movable ice-chest C laterally and flows under its bottom e, passes at the lowest point 80 of the inverted-dome-shaped cylinder-bottom b, through an elbow-pipe i, into a second cylinder or container G, in which, with the object of attaining a further cooling, there is inserted a cooling vessel H, which is always 85 filled with the water resulting from the melting of the ice, which ice-water flows through the vessel H, which extends nearly to the bottom of the container G, while from the upper part of said cooling vessel H a discharge-pipe 90 h conveys the warmer water to the outside into a separate water-container N. The beer passes from the beer vessel G, by means of a pipe g, to the draw-off tap g', and in order that the temperature of the beer when being discharged may be conveniently ascertained a thermometer K is introduced in proximity to the draw-off tap, the tube k of which thermometer is immersed in the beer in the vessel G.

In order that the amount of beer in the cylinder B and the position of the movable ice-chest C in the latter may at any time be easily ascertained by the attendant, a liter-scale M'

is arranged behind the draw-off tap on the outer wall of the ice-chest, on which scale an indicating-finger travels, which is connected with the movable chest C by a cord M, carried over a pulley m. All the positions of the said chest are therefore automatically indicated on the scale, so that the attendant is always precisely informed how much beer there is in the beer-container. In order that both the large vessel B and also the smaller beer-container G may be aerated and eventually entirely discharged—for instance, for the purpose of being cleaned—an elbow-pipe D is arranged on the vessel B within the movable ice-chest or piston C, opening directly under the washer-ring c', which elbow-pipe has an air-tap d', connected by a tubular nozzle, and carries below the latter a back-pressure valve d''. Said valve is normally kept closed by the back pressure of the liquid or beer in the cylinder or container B and is for the purpose of preventing access of air to the said cylinder during the time any beer is contained in the same. The same arrangement is provided for the vessel G by means of a pipe Q opening into the same and fitted with a back-pressure valve q' and a hose-pipe tap q. In order to aerate the vessels, an air-pump or the like is connected by a hose-pipe with the back-pressure valves d'' and q', respectively, and air is forced into the vessels B and G. When the vessel B has been first emptied, the cocks i' and i'' of the tubular connection i between B and G are closed, and then the vessel G is subjected to pressure and emptied. In order to fill the vessel B, there is used a pipe o, mounted on the connecting-pipe i and having a vessel O, air-admission tap o', and filling-tap o'', on the tread of which the filling hose-pipe from the cask is screwed. The vessel O of the filling-pipe and the tap q for discharging the vessel G are arranged in a separate chest or box A³, placed at the side of the sideboard-like projection A' in proximity to the draw-off tap g' in such a way as to be concealed from view, said box A³ being easily removable. In order to draw off the water produced by the melting of the ice from the movable ice-chest or piston C into the water vessel H suspended in the beer-container G, a suction-pipe E is employed, which extends upwardly over a pulley e' at the top of casing C', with one end thereof reaching to the bottom of said movable chest C. Said pipe is protected from injury on the inner side of said casing by means of a sheathing e'', fastened to the latter, and it (the pipe) is connected at its other end with the chamber of a pump W or other exhausting device. Reaching from said pump and extending almost to the bottom of the vessel H is another pipe or tube E', through which the cold water pumped from the movable ice-chest is caused to pass into said vessel, while the warmer water is carried off from the top of the latter by means of a pipe h. The spindle of the pump W is carried

through the side wall of the refrigerator-chest and has a hand-lever w outside the said chest for operating the pump. A large door T is arranged on the rear wall of the ice-chest A to allow of the cylinder B being inserted or removed—for instance, for the purpose of cleaning. In order that the tap i' of the tubular connection i may be conveniently opened after the opening of the door T, the key or lever i'' of the same is provided with a link i'', the handle of which lies in front in proximity to the door T, so that by pulling or pushing the link i'' the tap i' may be easily opened or closed.

Where the cylinders B are very large, it may be advisable in certain circumstances to arrange a separate ice-container in the ordinary manner in the upper part of the ice-chest A or in a construction arranged at one side, which is not shown in the drawings, so that the cylinders B may also be cooled by means of cooled air from the outside. Generally speaking, any further cooling is unnecessary.

Having now particularly described and ascertained the nature of my said invention and in what manner the same is to be performed, I declare that what I claim is—

1. In an apparatus for cooling and dispensing liquids, the combination with a refrigerator-chest, of a liquid-receptacle, a hollow piston working therein air-tight, and constituting a receptacle for ice, an additional liquid-receptacle, a cooling vessel therein, a pipe connecting the two said receptacles, a draft or draw-off pipe in the additional receptacle, and means for discharging the water resulting from the melting of the ice in the ice-receptacle into said cooling vessel.

2. In an apparatus for cooling and dispensing liquids, the combination with a refrigerator-chest, of a liquid-receptacle, a hollow piston working therein air-tight, and constituting a receptacle for ice, an additional liquid-receptacle, a cooling vessel therein, a pipe connecting the two said receptacles, a draft or draw-off pipe in the additional receptacle, a pump, a suction-pipe leading from the pump and extending to the bottom of the ice-receptacle, and a discharge-pipe also leading from the pump and discharging at the bottom of said cooling vessel.

3. In an apparatus for cooling and dispensing liquids, the combination with a refrigerator-chest, of a liquid-receptacle, a hollow piston working therein air-tight, and constituting a receptacle for ice, an additional liquid-receptacle, a cooling vessel therein, a pipe connecting the two said receptacles, a draft or draw-off pipe in the additional receptacle, and means for discharging the water resulting from the melting of the ice in the ice-receptacle into said cooling vessel, the said ice-receptacle being provided internally near the bottom with a support for the ice.

4. In an apparatus for cooling and dispensing liquids, the combination with a refrigerator-

ator-chest, of a liquid-receptacle, a hollow piston working therein, and provided internally near the bottom with an ice-support, an additional liquid-receptacle, a cooling vessel therein, 5 a pipe connecting the two said receptacles, a draft or draw-off pipe in the additional receptacle, a pump, a suction-pipe leading from the pump and extending to the bottom of the piston, and a discharge-pipe also leading from the pump and discharging at the bottom of said cooling vessel.

5. In an apparatus for cooling and dispensing liquids, the combination with a refrigerator-chest, of a liquid-receptacle, a hollow piston 10 working therein air-tight, and constituting a receptacle for ice, an additional liquid-receptacle, a cooling vessel therein, a pipe connecting the two said receptacles, a draft or draw-off pipe in the additional receptacle, a 15 pump, a suction-pipe leading from the pump and extending to the bottom of the ice-receptacle, a discharge-pipe also leading from the pump and discharging at the bottom of the cooling vessel, and means for counterbalancing the weight of said ice-receptacle.

6. In an apparatus for cooling and dispensing liquids, the combination with a refrigerator-chest, of a liquid-receptacle, a hollow piston 20 working therein air-tight, and constituting a receptacle for ice, an additional liquid-

receptacle, a cooling vessel therein, a pipe connecting the two said receptacles, a draft or draw-off pipe in the additional receptacle, a pump, a suction-pipe leading from the pump and extending to the bottom of the ice-receptacle, a discharge-pipe also leading from the pump, and discharging at the bottom of the cooling vessel, and means for aerating each of said liquid-receptacles.

7. In an apparatus for cooling and dispensing liquids, the combination with a refrigerator-chest, of a liquid-receptacle, a hollow piston working therein air-tight, and constituting a receptacle for ice, an additional liquid-receptacle, a cooling vessel therein, a connecting-pipe between the two said receptacles, a draft or draw-off pipe in the additional receptacle, and means for discharging the water resulting from the melting of the ice in the ice-receptacle into said cooling vessel, 45 the said connecting-pipe being provided with the cocks i' and i'' , and the latter being provided with a link and operating-rod.

In testimony whereof I affix my signature in presence of two witnesses.

WILHELM BACHNER.
